UNITED STATES PATENT OFFICE

ERWIN W. LAMB, OF LANSING, MICHIGAN.

PORTABLE ELECTRIC LAMP

1,195,032.

Specification of Letters Patent. Patented Aug. 15, 1916.

Application filed February 26, 1916. Serial No. 80,682.

To all whom it may concern:

Be it known that I, ERWIN W. LAMB, a citizen of the United States, residing at Lansing, in the county of Ingham and State of Michigan, have invented certain new and useful Improvements in Portable Electric Lamps; and I do hereby declare the following to be a full, clear, and exact description of the invention, such as will enable others skilled in the art to which it appertains to make and use the same.

This invention relates to new and useful improvements in portable electric lamps and the principal object of the invention is to provide a lamp which may be readily transported and is particularly attractive in appearance.

Another object of the invention is to provide a lamp which may be readily constructed of any suitable wood or other desirable material and which is particularly simple in construction and may be easily put together.

A further object of the invention is to provide a novel means for supporting the controlling switch in the base of the lamp which may be readily attached or removed therefrom at the desire of the user.

With these and other objects in view, the invention consists in the novel combination and arrangement of parts which will be fully set forth in the following specification and accompanying drawings, in which:—

Figure 1 is a side view partly in section of a lamp constructed in accordance with this invention. Fig. 2 is an edge view of Fig. 1. Fig. 3 is a bottom plan view of the lamp base. Fig. 4 is an enlarged sectional view through a fragment of the base showing the method of supporting the switch in place, and Fig. 5 is a detail perspective view of the switch supporting hood.

Referring to the drawing the numeral 1 designates as an entirety the lamp stand consisting of the base block 2. This base block is provided in its under side with a plurality of openings 3 which are arranged near one edge and are adapted to receive plugs of lead or other suitable weighting material 4. A rectangular recess 5 is formed in the block and opens outwardly through the bottom face thereof and this recess extends upwardly a distance equal to substantially one-half of the thickness of the base block and then is reduced as at 6 to form a shoulder 7, the use of which will appear as the description proceeds. The reduced por-

tion of said aperture extends to a point near the upper face of the block and a central circular opening 8 extends through the wall between the upper face of the block and the upper terminal of the reduced portion as clearly shown in Fig. 4. Formed in the block and extending from the rear wall of the opening 5 rearwardly to a point in alignment with the opening in the standard which will be more fully hereinafter described is a bore 9 which forms a conduit through which the wires which will be more fully herein-after described extend. Secured to the upper face of the block and spaced a distance from the rear edge equal to the distance from which it is spaced from the side edges is a suitable plinth 10 provided in its upper surface with a recess 11 for the reception of the extension on the standard which will be more fully hereinafter described. This plinth is attached to the base 2 by suitable screws or any other attaching means and is provided with a central opening 12 which aligns with the opening 13 which communicates at its lower end with the bore 9, and is formed in the base block 2. The standard is designated by the numeral 14 and comprises a rectangular strip of wood or any other suitable material having extending upwardly therein an axial aperture or bore 15 which aligns with the opening 12 in the plinth 10 and cooperates therewith in forming a conduit for the conductor wires.

The bore 15 extends upwardly through the standard 14 to a point substantially one-third of the length of the standard from the upper end thereof as clearly shown in Fig. 1. Formed in the upper end of the standard and extending transversely therethrough is an opening 16 for the reception of the rear end of the supporting arm 17. This supporting arm is preferably rectangular in cross section as shown in Fig. 2 and is secured in the opening 16 in any suitable manner. A brace rod 18 extends from a point below the opening 16 in the standard 14 to a point intermediate the ends of the supporting arm and this brace rod is formed with an opening 19 which communicates at its lower end with the opening 20 which is formed at the upper terminal of the bore 15 and extends upwardly and forwardly therefrom in the standard 14. The upper terminal of the opening 19 opens into the bore 21 formed in the arm 17 which inclines upwardly and forwardly and at its forward

end communicates with the downwardly and forwardly inclined bore 22 which leads to the end of the lamp socket 23 through which the conductor wires pass. It will thus be seen that a continuous conduit or duct is formed in the base, standard, brace and arm for the reception of the conductor wire which feed the lamp bulb with the electric current.

10 In order to support the switch in place in the openings 5 and 6 of the lamp base, the hood illustrated in Fig. 5 is provided and consists of a plate 24 provided at opposite edges with the downturned walls 25 which are formed at the lower edges with the flanges 26 having openings 27 formed therein. These openings 27 are for the reception of the attaching screws 28 and the hood is shaped to fit the recess 6 while the flanges 20 extend outwardly to a point near the walls of the openings 5 and bear against the shoulders 7 to which they are connected. The top or plate 24 of the hood is formed with a central aperture 29 for the reception of the threaded stem 30 of the switch designated by the numeral 31. A suitable adjusting nut 32 is threaded on the stem 30 on the inner side of the hood and the lock nut 33 is threaded on the stem on the outer side of the hood and it will thus be seen that the hood will be clamped between the nuts, thereby firmly supporting the switch 31 in place. The switch button 34 extends through the stem 30 and when moved upwardly in the position shown in Fig. 4, permits the current to flow through the wire 35 and to the light and when pressed downwardly breaks the circuit.

It will be apparent from the foregoing that a particularly simple and efficient means for supporting the switch in place in the

lamp base is provided which will allow the same to be readily removed and replaced at the desire of the user.

While in the foregoing there has been shown and described the preferred embodiment of this invention, it is to be understood that such changes may be made in the combination and arrangement of parts as will fall within the spirit and scope of the appended claim.

What is claimed is:—

In a lamp of the class described, a base having a recess near its forward edge extending upwardly from its lower face, a reduced recess extending upwardly from the first mentioned recess to a point near the upper side of the base, shoulders formed at the juncture of the recesses, the base also having an opening extending through the top and communicating with the reduced recess, said opening being arranged centrally of the recess, a hood comprising a body, side walls formed on the body, the body also having a central aperture therein alining with the aperture in the upper end of the reduced recess, flanges on the lower ends of the walls for engaging the shoulders, screws adapted to pass through the flanges to hold said hood in place, a switch, a reduced neck on the switch adapted to extend through the aperture in the hood and lock nuts for engaging opposite sides of the hood immediately adjacent the aperture to hold the switch in place.

In testimony whereof I affix my signature in presence of two witnesses.

ERWIN W. LAMB.
